UNITED STATES PATENT OFFICE

2,465,550

AIRCRAFT CARBURETOR

Andrew William Orr, Jr., Detroit, Mich., assignor
to George M. Holley and Earl Holley

Application February 18, 1946, Serial No. 648,301

7 Claims. (Cl. 261—39)

1

The object of this invention is to provide explosive mixtures which will be satisfactory when the pressure in the air entrance is above 30" of Hg, that is to say, at 40, 50, 60 and even 70" of Hg, which means that the air density is increased from $\frac{3}{40}$ of a pound per cubic foot, which is normal at sea level, 30" Hg, to $\frac{4}{40}$, $\frac{5}{40}$, $\frac{6}{40}$ or $\frac{7}{40}$ of a pound per cubic foot.

A further object is to combine this invention with the prior art in which barometric means are provided to correct the mixture ratio as air density in the air entrance falls from $\frac{3}{40}$ to $\frac{4}{40}$ to $\frac{1}{40}$ pound per cubic foot or even less.

A further object of this arrangement is to secure correct metering in the air density range where the relationship of air flow versus metering differential can be expressed by the equation

$$Wa = \frac{1}{K_1} \sqrt{d(P_e - P_t)}$$

by applying air density correction on the fuel differential side and by applying air density correction on the air differential side in the range where the relationship of airflow to metering differential is more accurately expressed by the equation

$$Wa = \frac{1}{K_2} \frac{P_e}{\sqrt{T_e}} \sqrt{\left(\frac{P_t}{P_e}\right)^{2/K} - \left(\frac{P_t}{P_e}\right)^{\frac{K+1}{K}}}$$

Wa=weight of air per second.

K₁=constant depending on units used.

K₂=constant depending on units used.

d=density of the air.

P_t=Pressure in the throat of venturi.

P_e=Pressure in the air entrance. (These pressures are "absolute", that is, they are read against a vacuum.)

K=Constant for air=1.406

T_e=Temperature in air entrance (absolute).

This equals ordinary readings of a thermometer, plus 273 for °C. and plus 460 for °F.

A further object of this invention is to provide a carburetor having a density correction system such that the carburetor may be placed in between two stages of supercharging and all of the first stage pressure put on the carburetor entrance without affecting the carburetor metering.

A further object of this invention is to provide a density compensation system such that better temperature compensation is obtained. Inasmuch as an air filled bellows gives perfect temperature compensation only at the fill density, the disclosed density correction system uses two or more bellows with each bellows being filled to

2

a degree sufficient to give the best possible temperature correction over the portion of the density range wherein it is operating.

A further object of this invention is to provide a carburetor and a density correction system, such that the full value of the air metering differential is available for metering up to the point where compressibility enters into the square root relationship between airflow and metering differential. This makes possible a much larger carburetor for the same sea level metering differential, as low metering differential is one of the important limitations on carburetor size.

A further object of this invention is to provide a fuel metering system giving the highest possible absolute pressure on the fuel metering jets together with the lowest pressure drop through the carburetor.

This application is a continuation in part of the application filed April 14, 1945, Serial Number 588,359, now abandoned.

The figure shows all the essential elements of my invention.

In the figure, air enters at 10 through venturi 11, flows past a small venturi 12, past a throttle 13 to the inlet to the supercharger. An air diaphragm 14 is provided with sealing diaphragms 59 and 60 of a well-known type, and is balanced against a fuel diaphragm 15 in a well-known manner.

In an equally well-known manner, a partially-evacuated bellows 16 controls a valve 17, which valve 17 admits a limited amount of air at the pressure of the air entrance 10 from an annular air chamber 18 through a pipe 19 to the chamber 20 to the right-hand side (suction side) of the diaphragm 14. Impact tubes 51 and drain holes 58 are provided for obvious reasons.

A passage 21 is connected to the throat of the small venturi 12 and to the passage 19. A valve 22 admits suction to the chamber 20 and is controlled by a diaphragm 23, a spring 24 and an opposing spring 41. At high suction in 12, there is automatically an increase in the area of the

valve 22 between the pipe 21 and the passage 19. The chamber 18 communicates directly with the pressure chamber 25 to the left-hand side of the diaphragm 14. The diaphragm 14 thus responds to air flow, and the effect of air flow is corrected for changes in air density by reason of the evacuated bellows 16, which expands at high altitudes and is adjusted to cooperate with valve 22.

My invention consists in supplementing and to some extent substituting for the bellows 16 another bellows 26, which is of a similar type to that

of the partially-evacuated bellows 16, and like the bellows 16 is located in the air entrance so that it responds to the pressure and to a certain extent to the temperature of the entering air. The air enters the chamber surrounding the bellows 16 through an opening 51 and escapes through an opening 49. Air enters the chamber surrounding the bellows 26 through an opening 52 and escapes through an opening 50. The bellows 26 controls a valve 27, which admits fuel under pressure from the pipe 28, which is connected to a chamber 29 to the right-hand (pressure) side of the fuel diaphragm 15.

The chamber 29 communicates with a source of fuel under pressure 38 through a pipe 31. The fuel flowing by the valve 27 descends through the pipe 32 through the chamber 33, which is the suction chamber on the left-hand side of the diaphragm 15, and descends through the restriction 34 to the fuel outlet 35, downstream of a main fuel restriction 36. The fuel flowing out of 35 flows by the loaded valve 37 along the passage 38, past the pressure-controlled valve 39, to the fuel outlet 40, which delivers the fuel to the center of the supercharger in a well-known manner.

Servomotor valve 41 controls the valve 37 by controlling the pressure acting to the left of the diaphragm 42. The pipe 56 conveys fuel from this chamber 44 to the valve 41. A passage 43, through the center of the valve 37, supplies fuel to the valve 41. Passage 43 connects the valve 41 to the pipe 38. The pipe 46 to the left of the restriction 36 connects the chamber 35 with the chamber 54 to the right of the diaphragm 55, which controls the valve 39. 45 is a spring imposing a load on the diaphragm 42 and thus on the valve 37. The spring 53 supports the valve 39.

Operation

When excessive air flow takes place, the diaphragm 14 moves to the right and the valve 41 then permits fuel to flow from opening 48, through chamber 44, along pipe 56, down pipe 43 to pipe 38, past valve 39 to pipe 40, which permits the valve 37 to open in a well-known manner. Hence the pressure drop due to the quantity of fuel flowing through restriction 36 is balanced against the drop in air pressure due to air flowing through the air entrance 18, venturi 11 and small venturi 12. When the valve 27 is opened, as it is when the air entrance pressure rises above that at approximately 11,000 feet, then fuel flows through the restriction 36 and also through the restriction 34. The fuel flowing through restriction 36 is balanced against the air flowing through venturis 11 and 12. Hence the fuel flowing through restriction 34 around the bypass 20—27—32 reduces the effect of the pressure drop through 36, and to that extent renders the mixture richer than it otherwise would be. However, dense air automatically renders the mixture lean. Hence, this leanness is offset.

The value of this invention is that at high boost pressure in the air entrance, that is, the air pressure which would occur during a dive due to ramming action, will have a tendency with the orthodox fuel control means, such as the bellows 16, to give a lean mixture. When the air density in the air entrance is above .055 pound per cubic foot, bellows 26 in conjunction with the needle 27 and restriction 34 increases the fuel differential across jet 36 compared with that of the fuel differential across diaphragm 15 and air differential across diaphragm 14 in such a manner as to compensate for the increased air density. Valve 75

27 operating in conjunction with bellows 26 can be opened to cover the increase in air density existing at 40", 50", 70" or even 100" Hg or higher. Inasmuch as these high top deck pressures are used in a system where ram from a supercharger is applied to the carburetor entrance to obtain maximum amount of power, this carburetor imposes no restriction upon the military output of the engine because the metering differential at the high airflows even at very high entrance densities is sufficient for metering. Obviously, a condition might arise where the bellows 26 could be used without the bellows 16. For example, if a plane operated only at sea level or in the vicinity thereof.

Temperature correction

In the operation of this device I have discovered that the best all around temperature correction is obtained when the air in the barometric element 26 has a density of .075 pound per cubic foot and the barometric element 16 has a density of .035 pound per cubic foot. If another gas is used (such as nitrogen) a corresponding value would be given for the density of the gas inside the bellows. For example, with nitrogen the value would be .0725 for bellows 26 and for bellows 16 the value would be .0338. In the cases where air is used the density in bellows 26 can have a range from .06 to .09 and in the bellows 16 from .025 to .055.

Further in the operation of this device I have discovered that it is best to arrange that when the pressure in the air entrance falls to 20" (mercury) that the bellows 26 should move valve 27 so as to close the passage 32. At this moment the valve 11 should begin to open as the bellows 16 expands. (This corresponds to an air entrance density of approximately .055 pound per cubic foot.) Under this condition the suction in the low pressure chamber 20 is equal to the suction in the throat of the venturi 12.

Now, I have further discovered that at an altitude corresponding to an air entrance density of .045 that the suction in chamber 20 should be approximately 75% of the suction in the venturi 12.

As higher air flows under these conditions the required suction in chamber 20 should be reduced by about 1% but actually it falls off 3% in value if the opening around valve 22 was fixed in area. The mixture thus would become slightly lean. The opening around valve 22 is therefore increased in area as the diaphragm 23 rises slightly. The increase in area around valve 22 maintains the mixture at the desired fuel-air ratio.

At extremely high altitudes the velocity of flow of air through the venturi for a given quantity of air in pounds per hour increases, and at the same time the density of the air in the air entrance decreases. The net result of these facts is that the valve 22 should open slightly so as to maintain the desired fuel-air ratio.

What I claim is:

1. In a carburetor having an air entrance and a venturi therein, an air chamber, an air diaphragm therein, means for applying Venturi suction to one side of the diaphragm and atmospheric pressure to the other, a fuel chamber, a fuel diaphragm therein, a fuel entrance, a fuel passage, a restriction therein, a passage connecting one side of the fuel diaphragm with the pressure on the upstream side of said fuel restriction, a passage connecting the other side of the fuel diaphragm with the downstream pressure

of said fuel restriction, means interconnecting the two diaphragms whereby the movement of one diaphragm opposes the movement of the other diaphragm, a fuel flow control valve located in series with said fuel restriction, operating means for said valve jointly controlled by the two opposing diaphragms whereby an increase in pressure difference across said fuel restriction tends to close the valve and an increase in the Venturi suction tends to open said valve so as to maintain a preselected fuel/air ratio, a bypass around said fuel restriction, a valve in said bypass, barometric means comprising an expansible chamber filled with gas and having flexible walls, a connection from the expansible chamber to said valve in said bypass, said expansible chamber being located in the air entrance so as to be responsive to the air entrance pressure when said pressure is greater than a preselected pressure between that of sea level and that corresponding to the pressure at which the relationship between airflow and Venturi suction no longer follows the square root proportional law, said barometric means being adapted to open said bypass valve in response to said air entrance pressure, a second barometric means comprising a second expansible chamber filled with gas and having flexible walls also located in said air entrance and a valve connected to said second expansible chamber of said second barometric means adapted to bleed air entrance air into the low pressure side of said air diaphragm when the air entrance pressure corresponds to an altitude greater than the altitude at which the first mentioned barometrically controlled valve ceases to operate.

2. A device as set forth in claim 1 in which the first mentioned barometric element is a bellows filled with air having a density of approximately .075 pound per cubic foot and in which the second barometric element is a bellows filled with air having a density of approximately .035 pound per cubic foot.

3. A device as set forth in claim 1 in which the first mentioned barometric element is a bellows filled with air having a density between .06 and .09 pound per cubic foot and in which the second barometric element is a bellows filled with air having a density between .025 and .055 pound per cubic foot.

4. A device as set forth in claim 1 in which there is a valve located in the passage connecting said venturi and the low pressure side of the air diaphragms, a diaphragm connected to said valve, a passage admitting air at the air entrance pressure to one side of said diaphragm, the other side of said diaphragm being subjected to Venturi suction, yieldable means engaging with said diaphragm so as to oppose the pressure of the air in the air entrance acting against the Venturi suction.

5. A device as set forth in claim 1 in which the first mentioned barometric element is a bellows filled with air having a density of approximately .075 pound per cubic foot and in which the second barometric element is a bellows filled with

air having a density of approximately .035 pound per cubic foot and in which there is a valve located in the passage connecting said venturi and the low pressure side of the air diaphragms, 5 a diaphragm connected to said valve, a passage admitting air at the air entrance pressure to one side of said diaphragm, the other side of said diaphragm being subjected to Venturi suction yieldable means engaging with said diaphragm so as to oppose the air entrance pressure.

6. A device as set forth in claim 1 in which the first mentioned barometric element is a bellows filled with air having a density between .06 and .09 pound per cubic foot and in which the second barometric element is a bellows filled with air having a density between .025 and .055 pound per cubic foot and in which there is a valve located in the passage connecting said venturi and the low pressure side of the air diaphragms, a diaphragm connected to said valve, a passage admitting air at the air entrance pressure to one side of said diaphragm, the other side of said diaphragm being subjected to Venturi suction yieldable means engaging with said diaphragm so as to oppose the air entrance pressure.

7. Fuel control means for an airplane carburetor having an air venturi, an air diaphragm responsive to the depression created by the said venturi, a fuel supply under pressure, a fuel entrance, a fuel restriction therein, a fuel diaphragm responsive to the drop in pressure created by the restriction, a pilot valve operated by both of said diaphragms acting in opposition to each other, a fuel flow regulating valve located downstream from said fuel restriction, a third diaphragm connected to said fuel flow regulating valve, yielding means adapted to close said fuel flow regulating valve, a chamber adjacent to

30 said third diaphragm, a restricted passage connecting said chamber with the fuel under pressure in said entrance, a passage leading out of said chamber through said pilot valve and returning to the downstream side of said fuel flow regulating valve, a fourth diaphragm, a pressure 35 regulating valve connected thereto and located downstream of said fuel flow regulating valve, yielding means tending to open said pressure regulating valve, a chamber associated with said fourth diaphragm, the pressure in said chamber being adapted to close said pressure regulating valve, a passage connecting said last mentioned 40 chamber with the downstream side of said fuel restriction whereby the pressure necessary to open said pressure regulating valve falls at high 45 fuel flows by an amount equal to the drop in pressure at said fuel restriction.
